FOOT COVERING

Raymond F. Trimble, Philadelphia, Pa.

Application May 2, 1938, Serial No. 205,602

1 Claim. (Cl. 36—9)

This invention relates to slippers or foot covering and has for its primary object the provision of an efficient and inexpensive moisture-proof foot covering substantially in the shape of a slipper which may be readily worn on the foot over hosiery and within a shoe to prevent the foot from becoming damp from a shoe which has become wet for lack of an overshoe or may be employed for aiding in fitting of new shoes, especially where the hosiery is wet or damp from perspiration, allowing a shoe of a correct size to be easily placed on the foot with comfort and eliminate the possibility of fitting the foot with a shoe which is too large and further will materially aid in the prevention of the spread of foot diseases, frequently contracted from new shoes previously tried on by a person having foot disease.

With these and other objects in view, the invention consists in certain novel features of construction, combination and arrangement of parts to be hereinafter more fully described and claimed.

For a complete understanding of my invention, reference is to be had to the following description and accompanying drawing, in which

Figure 1 is a plan view illustrating a blank from which the present invention is constructed.

Figure 2 is a perspective view illustrating the foot covering constructed in accordance with the present invention.

Referring in detail to the drawing, the numeral 5 indicates a foot covering substantially in the shape of a slipper, as shown in Figure 2, and is made from cellulose material, commonly known as "Cellophane," so as to be moistureproof and of a comparatively thin upper and sole construction so that the covering 5 may be slipped on a foot over the usual hosiery and worn within a shoe which is of the proper size for the foot.

The covering will prevent moisture from passing from the foot to the shoe or from the shoe to the foot. The material also permits the covering to be easily folded to facilitate carrying of the covering in a pocket of a garment or within a lady's handbag, so that it will be handy for immediate use when needed in wet weather. The covering when employed in shoe stores for trying on new shoes may be conveniently stored in large quantities in a carton or the like and after being once used may be discarded or destroyed without materially increasing operating cost and will prove to be a great asset to a store as an advertising medium as well as an aid towards sanitation by the prevention of the spread of

foot diseases. Also due to the thinness of the material, the covering may be worn without discomfort within the shoe and will permit a new shoe of the proper size of a foot to be easily placed on the foot and especially when the hosiery worn on the foot is damp from perspiration. The danger of fitting a foot with too large a size of shoe will be materially reduced through the use of this covering.

The covering consists of a sole 6 and an upper, 10 the latter including a counter 7, sides 8 and a combined toe and instep portion 9. The sole, upper and combined toe and instep portion are made from a blank shaped as shown in Figure 1. The material of the blank is severed inwardly 15 from one end edge thereof, as shown at 10, and is further severed transversely, as shown at 11, and creased on the lines 11' to form attaching flaps 12 having adhesive 13 applied thereto. The cut 11 extends at right angles to the cut 10 and 20 connects with the inner end of the cut 10 intermediate the ends of said cut 11 so that when the material of the blank is folded on the lines 11' the flaps 12 are formed and said flaps may be brought to underlie the sole 6 and be secured thereto by the adhesive 13. The material of the blank is further creased on the lines 15, 16, 16' and 17' by folding the portions of the blank which lie outwardly of said lines 15, 16, 16' and 17' onto the portions of the blank which lie inwardly of 25 said latter-named lines. The material of the blank is further creased on the line 20 which 30 extends transversely of said blank. The material of the blank bordered by the crease lines 15, 16, 16', 17', 20 and the cut 11 constitutes the 35 sole 6. The material of the blank lying to the left of the crease line 20 in Figure 1 forms the combined toe and instep portion 9. The material of the blank which lies outwardly of the 40 crease lines 15, 16, 16', 17' forms the sides 8 and counter portions 17 of the upper and said material outwardly of said crease lines is brought to stand substantially vertically to the sole with the end edges A of the blank brought into slightly overlapped relation, as at 23, and secured together by adhesive 14. The flaps 12 pass under the sole 6 and are secured thereto as before stated. The counter portions 17 being secured together and the flaps 12 being secured to the sole 6 retain the sides 8 in substantially upright 45 position with respect to the sole. The material of the sides 8 has free straight edges C and converging edges D. The straight edges C extend into the counter portions 17 to meet the straight edges A. The material of the blank is cut in- 50

wardly, as at 19', from the edges D to the crease lines 16' and 17' to form attaching portions 19 and 21 having adhesive applied thereto, as shown in Figure 1. The crease lines 15 extend from the juncture of the crease lines 11' and the cut 11 to the edges C with the crease lines 16 connecting therewith inwardly of the edges C. The material of the blank lying between the edges C and the crease lines 16 is creased on lines 22, 22' and 23'. The crease lines 22 and 22' extend from the edges C in converging relation and meet the crease lines 16 and 16' at the juncture of said crease lines 16 and 16', as shown at E. The crease lines 23' extend from the edges C to meet the crease lines 16 where the latter meet with the crease lines 15, as shown at F. The material of the blank when folded on the crease lines 16, 22, 22', 15 and 23' provides the sides and portions of the counter 7 with pleats H which act to permit the sides of the upper to expand and contract so that when the covering is placed on a person's foot the sides contact the sides of the foot and assist in retaining the covering on the foot.

25 The combined toe and instep portion 9 folds on the crease line 20 to overlie a portion of the sole 6 with the attaching portions 19 and 21 overlying portions of said toe and instep portion 9 and being secured thereto by the adhesive on said portions 19 and 21 which adhesive fastens said combined toe and instep portion in place upon said toe and instep portion 9 to overlie the toes and instep of the person's foot when the covering is applied to the foot.

30 35 After the blank has been made into the foot covering as shown in Figure 2, the sole 6, combined toe and instep portion 9 and counter 7 may be folded on the line 23 to decrease the size of the covering for storage and other purposes 40 and it may be readily unfolded for use when desired. When the covering is positioned on a supporting surface, the point of contact of the sole 6 with said supporting surface will be substantially along the fold line 23 due to the sole 45 sloping upwardly from each side of said fold line as indicated by the shading G in Figure 2. The upward sloping of the sole as specified is caused by the counter portions 17 and sides 8 being brought into position for forming the sides and counter 7 of the upper.

50 It is believed that the foregoing description, when taken in connection with the drawing will fully set forth the construction and advantages of this invention to those skilled in the art to which such devices relate, so that further detailed description will not be required.

Having thus described the invention, what I claim is:

In a foot covering, a blank including a first part of substantially rectangular shape and a second part integral with said first part at the front end thereof to provide a combined sole and toe-and-instep portion, said first part including straight side edges and an end straight rear edge, said side edges converging towards the toe-and-instep portion with cuts extending inwardly from said converging edges for a limited distance to form attaching flaps having adhesive thereon and foldable to overlie and adhere to said combined toe-and-instep portion, said first part being cut inwardly from the straight rear end edge for a limited distance and transversely thereof for a limited distance with the first and second cuts connecting at the front end of said first cut to provide two flaps at the rear of said blank, which flaps are foldable on crease lines paralleling the cut extending inwardly from the rear edge and positioned at the ends of said transverse cut to coact with said cuts in providing attaching flaps having adhesive thereon, said attaching flaps being adapted to underlie and be secured to the rear portion of said first part, said first part being foldable on crease lines extending from the ends of said transverse cut through the straight side edges to coact with the cut extending inwardly from the rear edge in providing counter portions having their rear edges capable of being brought to overlap and of being secured to each other to complete a counter of an upper, said first part having crease lines connecting with the second-named crease lines and spaced from said straight side edges and the converging edges and extending to the toe-and-instep portion to permit folding of said first part to form sides of the upper and a sole, said first part having a crease line extending forwardly from each of the junctions of said second named crease lines with the straight side edges of said first part and each such crease line joining one of said third-named crease lines substantially centrally thereof, said first part having another plurality of crease lines extending forwardly from the straight side edges of said first part somewhat forwardly of said junctions to the point of juncture between said third and fourth named crease lines, and another plurality of crease lines extending substantially perpendicularly to the straight side edges of said first part and joining the junctures between the second and third named creases to permit folding of the sides of said first part to provide pleats in said sides of the upper and forward portions of the counter, said pleats acting to permit expansion and contraction of the sides and forward portions of the counter.

RAYMOND F. TRIMBLE.
